UNITED STATES PATENT OFFICE.

PIERRE ZUCCO, OF NEW YORK, N. Y.

COLLAPSIBLE FORM.

980,389.

Specification of Letters Patent.

Patented Jan. 3, 1911.

Application filed May 11, 1907. Serial No. 373,115.

To all whom it may concern:

Be it known that I, PIERRE ZUCCO, a citizen of the Argentine Republic of South America, a resident of the city of New York, county of New York, State of New York, have invented certain new and useful Improvements in Collapsible Forms, of which the following is a specification.

My invention relates to collapsible forms, and the means by which said forms may be employed for the building of reinforced but otherwise unsupported concrete floors and the like.

It consists in the combination of parts, and in details of construction which will be more fully explained by reference to the accompanying drawings, in which—

Figure 1 is a perspective view of my device. Fig. 2 is a modification. Fig. 3 is a detail.

Various arrangements of false work, and similar devices have been employed for constructing concrete floors where supporting metal I-beams form a portion of the structure, for arches of sewers, and like work.

It is the object of my invention to provide a cheap and ready means for constructing floors and like surfaces over considerable areas where no steel beams or equivalent supports may be had, and to so construct the forms used that they may be rapidly removed after one section has been constructed, and employed for other sections without going to the expense of the great amount of material necessary to finish the whole structure at once.

In carrying out my invention, I first employ horizontally disposed planks 2 which are placed upon posts or supports 1, resting upon the floor or surface below and having such length as to support the planks 2 at the proper height for the proposed structure. These planks are laid, and the structure completed in the following fashion: One of the planks and its supports being secured, an intermediate distance-piece of any description, is placed between this and the next plank so as to temporarily maintain a proper distance apart.

My collapsible forms may be made in two or more sections 3 which are preferably connected with a transverse top section 4. The side sections 3 are notched or formed to engage with the edges of the plates or planks 2, such notches being indicated at 5, and in

order to maintain these parts in engagement, to prevent their slipping off the edges of the planks, intermediate struts of various forms may be used, such as shown at 7, where the braces are rigid bars, or they may be in the form of turn-buckles, or equivalent devices as at 6; the object being in any event to maintain these parts in proper relation with their supports and plates 2. These sections 3 and 4 are then covered with boards, or coverings as shown at 8 and 9; the side portions of the coverings 8 resting against the sides 3, and the top portion 9 resting upon the upper part; there being a set of the supports 3 and 4 at each end of the sections so that a temporary rough arch is formed. The next contiguous length of said arch is formed in like manner until the distance over which the structure is to extend, has been covered.

In some cases I may use wooden sides as 8, and the top 9 may be made of sheet metal, and it is also competent to make the entire portion, represented by 8 and 9, of sheet metal, the edges being turned to form offsets as at 10, so that the shoulders thus formed may rest upon the plates or planks 2 in the same manner as previously described.

The structure is thus built up in lengths until it is entirely completed to cover the desired surface, and thus far consists only of a temporary false work.

The object in offsetting the lower ends as at 5, is to insure the engagement of the supports with the plates 2; because in the work of placing the concrete, the workman must pass over all this portion, and it is necessary that it be stiff enough to allow such passage before the concrete is placed. As soon as this false work has been erected, the concrete is filled in to form the structure, as shown in the figures, and after setting for a short time, the portions forming the arches between the concrete beams, may be removed, and used again at a point farther along, but the plates 2 and the supporting stanchions 1 will not be removed until the material has had sufficient time to set, so that it will be entirely self-supporting.

In building a structure of this description, as soon as two or three of the sections of false work have been erected, the concrete may be placed upon them, and by the time a few sections have been completed those

first finished will be set sufficiently to allow the collapsible forms to be removed, and placed farther along in the work which is the great point of economy claimed in this construction.

If metal sheets are employed to form the covering said sheets may be bent as previously described, having the offset or shoulder ends for support, and the sheets may 10 have supplemental narrow strips 9^a secured in any suitable manner to their alternate ends in such a manner that one of said sheets being in place, with its strip projecting, the end of the next portion of the form may be 15 slipped over this strip which thus forms a support for it, and so on to the length of the required structure.

It will be understood that the concrete which forms the permanent structure may 20 be reinforced by the introduction of rods, wires, plates, strips, or any desired form of

metallic reinforce; such reinforce being illustrated in Fig. 2.

Having thus described my invention, what I claim as new and desire to secure by Letters Patent is:—

In an apparatus for forming concrete arches, an interdependent structure capable of indefinite extension, said structure including parallel spaced planks, independent 30 arches, connecting means between the interior walls of the arches, means engaging the edges of the arches with the edges of the plank supports, independent vertical posts upon which the planks rest, and means 35 connecting the adjacent ends of arch sections in the direction of their length.

PIERRE ZUCCO.
